UNITED STATES PATENT OFFICE

2,579,159

ROLLER SCREEN

Winfield J. Starr, Philadelphia, Pa.

Application September 8, 1949, Serial No. 114,600

8 Claims. (Cl. 160—269)

1

The present invention relates to roller screens and the like for windows.

A purpose of the invention is to provide for more effective locking and tensioning of a roller screen.

A further purpose is to avoid marring the material of the roller screen.

A further purpose is to permit release of the clamping of a roller screen in case it receives impact.

A further purpose is to secure more positive clamping and unclamping of a roller screen.

Further purposes appear in the specification and in the claims.

In the drawings I have chosen to illustrate one only of the numerous embodiments in which my invention may appear selecting the forms shown from the standpoints of convenience in illustration, satisfactory operation and clear demonstration of the principles involved.

Figure 1 is a broken front elevation of the roller screen of the invention.

Figure 2 is a section of Figure 1 on the line 2—2.

Figures 3 and 4 are views corresponding to Figure 2 showing the cam and gripping strip in other positions.

Figure 5 is an end elevation of the gripping strip.

In the drawings like numerals refer to like parts.

My U. S. Patent No. 2,350,200, dated May 30, 1944, for screen holder illustrates a cam for gripping and tensioning a roller screen at the side of the screen. The cam acts directly on the screen and, although clamping can be continued for a considerable time, this device has a tendency to wear and abrade the screen slightly. By the present invention I obtained more positive clamping and tensioning action and greatly reduced the possibility of damage to the screen.

The roller screen 20 may suitably be of any convenient material such as wire or plastic screening of the character employed on insect screens for windows. The screen is supported and wound over a roller 21, which, except as herein noted, may be of the character shown in my patent, or of any character commonly used as a shade roller. It comprises a drum 22 of any suitable material such as wood, having a dead center pivot 23 in a suitable pivot fitting on the window frame 24, and having a spring operated squared pivotal end or pintle 25, in a suitable squared socket in the window, the end 25 being rotatable with respect to the remainder of the roller under the action of the internal winding spring not shown as well known.

2

The screen extends down below the roller and when in use will be pulled fully down, passing at both sides through the interior of a vertically extending housing 36 which cooperates with the trim 37 of the window and has an open edge 38 through which the screen extends.

In general the trim provides an adequate back against which the housing can operate, and it is not generally necessary to provide a back of the housing independent of the trim at the side of the window.

The housing extends vertically for substantially the full height of the screen to a point 49 slightly below the roller. The housing is desirably a sheet metal strip which is somewhat resilient and is provided with a base 41 secured to the window as by screws 42, and a combined shank portion and guiding surface 43 extending toward the center of the window and suitably curved and desirably semi-circular cam well 44 which forms a bulge or enlarged end running vertically on the front of the housing and an outer lip 45 which defines one side of the open edge. Positioned inside the housing or between the housing and the trim 37, desirably running the full length of the housing, is a resilient sheet metal gripping strip suitably of aluminum alloy, stainless steel, brass or copper, located in line with the open edge of the housing. When viewed in cross section the gripping strip has a back jaw 46 which is integrally connected by a U-bend 47 with a front jaw 48, the two jaws having an open end 50 through which the screen extends to a position between the jaws. The front jaw 48 is reversely bent at 51 at the end toward the middle of the window, and the reverse bend intermediate its ends deflects toward and into the cam well in a cam hump 52 and then terminates in a resilient heel 53 which in use engages the guiding surface 43 of the housing. The gripping strip is then located at one side of the cam well while the hump 52 enters the cam well, providing a jaw cam 54 on the side toward the center of the window and a jaw cam 55 on the side remote from the center of the window.

Preferably the jaw cam 54 toward the center of the window is relatively more abrupt than the jaw cam 55 remote therefrom.

The cam well is occupied by a cam 56 which extends desirably for the full length of the housing and the gripping strip is curved and preferably semi-circular in cross section on its outer surface 57, and is hollow, curved and preferably semi-circular in its cross section in its inner surface 58. The edge 60 of the cam toward the

middle of the window is preferably suitably rounded as shown and the opposite edge 61 of the cross section is pointed to aid in releasing the jaw cam 55.

At a convenient position along the length of the cam 56, and suitably near the bottom of the window, the housing is recessed at 62 and a handle 63 attached to the cam on the surface 57 and preferably near the end 61 extends out through the recess in position to be grasped by the hand of the user.

The screen at the bottom is secured to a strip 64 which has recesses 71. The strip is sprung to engage hooks 72 in the sill 73 of the window, to hold the screen down against the pull of the roller spring where it is not desired to lock the cam at the sides.

In operation it will be understood that in equipping the window for the roller screen of the present invention suitable shade roller fittings or brackets will be placed at the upper part of the sash, the gripping strips, cams and housing will be assembled on opposite sides of the window as shown. The hooks 72 will be applied on the sill.

The screen is then assembled on the roller. The screen is then preferably rolled up on the roller until only a short length extends beyond the roller. Screen material should then be placed in the base strip 64.

To insert the bottom strip the roller is mounted in the roller fittings in the window and the bottom strip is applied at the top in the space between the front and back jaws of the gripping strip while the cam is in the non-locking position as shown in Figure 2.

The screen can then be pulled down, being guided at the sides and between the front and back jaws of the gripping strip. When the screen reaches the bottom it is held by the engagement of the hooks 72 in the recess 71 of the bottom strip.

To stretch the screen and lock the sides, the handles 63 are pulled toward the center of the window. This causes the near edge 60 of the cam to move from the non-locking position of Figure 2 to the locked position of Figure 3, at which position the edge 60 engages the near jaw of the gripping strip, compresses together the jaws of the gripping strip against the trim 37 and, pressing against the near cam 54, forces the gripping strip bodily outward to the position of Figure 3, stretching the screen laterally and locking and tensioning it.

In achieving the gripping or locking position the heel 53 of the gripping strip rides along the guiding surface 43 of the housing, guiding the unlocking cam 55 outwardly until it jams at 73 in Figure 3 against the near corner of the guiding surface. At the same time the outer end 47 of the U jams against the window 24. Due to the friction of the engaging parts, and the fact that the cam has moved beyond its center and is exerting an outward component on the jaw cam 54, the structure will sustain the position of Figure 3 indefinitely and hold the screen locked and stretched. Should however a very abnormal hold or impact be applied to the screen, as for example when the screen is struck by a baseball or stone, instead of tearing the screen, will pull through the jaws and absorb the energy of the impact. In order to restore the screen properly to the jaw it is then merely necessary to move the cam back to the neutral position of Figure 2

and roll the screen up to the top and pull it down again.

For the purpose of unlocking the handles on the cams they are moved outward to a position as shown in Figure 4. At this position the outer pointed end 61 penetrates between the cam well and the outer jaw cam 55, prying the unlocking cam 55 inwardly, and at the same time relieving the pressure of the locking cam end 60 of the cam 56 on the locking cam 54. The gripping strip then moves outwardly while the heel is guided against the guiding surface 53, releasing the grip on the screen and allowing gripping to move bodily to the center of the window as shown in Figure 2. It will thus be evident that when the gripping strip is tightened it closes and then pulls the screen outwardly, while when it is released it opens and moves inwardly. The range of motion is shown in the difference in positions between Figures 2 and 3.

It will be evident by comparing Figures 2 and 3 that the housing, being preferably of light gage sheet material, deflects forwardly and by its spring imparts gripping pressure on the gripping strip and on the cam to hold the parts in the locking position. This feature is preferable, although the device is operative without this resilience of the housing.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. A holder for locking and tensioning a roller screen comprising a vertically extending housing having an open edge and having a cam well curved in horizontal section, a vertically extending curved cam in the cam well, and a resilient gripping strip in line with the open edge having jaws open toward the open edge and located at one side of the cam well.

2. A holder for locking and tensioning a roller screen comprising a vertically extending housing having an open edge, having a guiding face in line with the open edge and having a cam well at one side curved in horizontal section, a vertically extending curved hollow cam in the cam well, and a resilient gripping strip in line with the open edge, having jaws open toward the open edge, located at one side of the cam well and having inner and outer jaw cams on the jaw adjoining the cam well.

3. A holder for locking and tensioning a roller screen comprising a vertically extending housing having in horizontal section an open edge, a cam well at one side curved in horizontal section and a guiding face on the portion of the housing remote from the open edge, a vertically extending curved hollow cam in the cam well, and a unitary sheet metal resilient gripping strip in line with the open edge, having U-shaped jaws open toward the open edge, located at one side of the cam well, and having on the jaw adjacent

the cam well a reverse bend having a hump provided with outer and inner jaw cam surfaces extending into the cam well and cooperating with the edges of the cam.

4. A holder for locking and tensioning a roller screen comprising a vertically extending hous-

ing having in horizontal section an open edge, a cam well at one side curved in horizontal section and a guiding face portion on the portion of the housing remote from the open edge, a vertically extending curved hollow cam in the cam well, a reverse bend on said holder terminating in a spring heel engaging the guiding face in one position.

5. A holder for locking and tensioning a roller screen comprising a vertically extending housing having in horizontal section an open edge, a cam well at one side curved in horizontal section and a guiding face portion on the portion of the housing remote from the open edge, a vertically extending curved hollow cam in the cam well, having a curved outer vertical edge and a sharp inner vertical edge.

6. A unitary sheet metal gripping strip for a roller screen comprising U-jaws one of which has a reverse bend near its outer edge, a reverse bend portion extending outside of the jaw having the reverse bend and a cam hump on the reverse bend.

7. A unitary sheet metal gripping strip for a roller screen comprising U-jaws, a reverse bend on one of the jaws, a cam hump on the reverse bend and a spring heel beyond the cam hump.

8. A unitary sheet metal gripping strip for a roller screen comprising U-jaws, a reverse bend on one of the jaws and a cam hump on the reverse bend having a relatively abruptly inclined outer jaw cam and a relatively gradually inclined inner jaw cam.
